175,428

VEGETABLE DISH COVER OR SIMILAR ARTICLE

Oscar W. Martha, Wallingford, Conn., assignor to R. Wallace & Sons Manufacturing Company, Wallingford, Conn., a corporation of Connecticut

Application April 15, 1955, Serial No. 35,528

Term of patent 14 years

(Cl. D44—15)

FIG. 1

FIG. 2

FIG. 4

FIG. 3

Fig. 1 is a top plan view of a vegetable dish cover showing my new design;

Fig. 2 is a side elevational view of the vegetable dish cover as shown when inverted and used as a dish;

Fig. 3 is a bottom plan view of the cover as shown in Fig. 1 and a top plan view of the cover as shown in FIG. 2;

Fig. 4 is a section taken on the line 4—4 of FIG. 1; and

Fig. 5 is a section taken on the line 5—5 of FIG. 1.

I claim:

The ornamental design for a vegetable dish cover or similar article, substantially as shown.
